(57) **CLAIM**

The ornamental design for, a bumper for an automobile, as shown and described.

DESCRIPTION

FIG. 1 is a front elevation view of a bumper for an automobile showing our new design;

FIG. 2 is a rear elevation view thereof;

FIG. 3 is a top plan view thereof;

FIG. 4 is a bottom plan view thereof;

FIG. 5 is a right side elevation view thereof; and,

FIG. 6 is a front perspective view thereof.

The left side elevation view thereof is symmetrically same to the right side elevation view above.
